224,328

COMBINED GOLF ACCESSORIES AND HOLDER THEREOF

Edward L. Cicero, 52-62 66th St.,
Maspeth, N.Y. 11378

Filed Sept. 9, 1970, Ser. No. 24,902

Term of patent 14 years

Int. Cl. D21—02

U.S. Cl. D34—5

FIG. 2

FIG. 4

FIG. 1

FIG. 3

FIG. 5

FIG. 1 is a view in side elevation for combined golf accessories and holder thereof showing my new design.

FIG. 2 is a plan view thereof, the bottom plan view being substantially similar.

FIG. 3 is a sectional view taken along line 3—3.

FIG. 4 is a partial end view showing pencil retaining hole.

FIG. 5 is an end view taken along line 5—5.

The golf tees in the central portion of the holder have been omitted for convenience of illustration.

I claim:

The ornamental design for combined golf accessories and holder thereof, as shown and described.
